A. G. SMITH

FOLDING TABLE

Filed March 22, 1921

UNITED STATES PATENT OFFICE.

ARTHUR G. SMITH, OF LOS ANGELES, CALIFORNIA.

FOLDING TABLE.

Application filed March 22, 1921. Serial No. 454,350.

To all whom it may concern:

Be it known that I, ARTHUR G. SMITH, a citizen of the United States, residing at Los Angeles, in the county of Los Angeles and State of California, have invented new and useful Improvements in Folding Tables, of which the following is a specification.

This invention relates to folding tables.

An object of the invention is to provide 10 a portable table particularly adapted for motorists, campers and the like that may be readily folded into a very compact form for transportation; the table comprising a top portion and a standard, each adapted 15 to be separably folded into compact form, the cover portion being adapted to serve as a casing for carrying the standard so that when the table is completely folded for transportation it presents a neat appearance 20 with only the smooth surface of the table exposed.

Another object is to provide a table of the above character embodying a standard adapted to be folded and disposed between 25 two hinged cover portions of the table in such a manner that the parts will be held securely to prevent vibration and rubbing of the parts when carried by hand or being transported in a vehicle.

30 A further object of the invention is to provide a table of the above character which is exceptionally strong and which may be made of comparatively few pieces, the nature of the pieces being such that they may 35 be cut from standard size of lumber with practically no waste.

Other objects will appear hereinafter.

The invention is illustrated by the accompanying drawings in which:

40 Figure 1 is a view in perspective of a table embodying the features of this invention.

Figure 2 is a view in elevation of the table in inverted position.

45 Figure 3 is a view in perspective showing the table completely folded for transporting.

Figure 4 is a view in section as seen on the line 4-4 of Figure 3.

50 Figure 5 is a view in section as seen on the line 5-5 of Figure 3.

Figure 6 is a view in detail section as seen on the line 6-6 on Figure 1.

More specifically 7 indicates a table top

which is formed of two similar sections or 55 panels 8 and 9, which are hinged together by hinges 10, placed on the under sides of these sections. The hinges are so positioned that the adjacent inner edges of the two sections abut one another when the table is 60 open so as to present a smooth surface and to provide rigidity. The two sections 8 and 9, may be of any suitable construction or material but are here shown as composed 65 of single pieces of lumber of oblong shape which are preferably of such proportions that they may be cut from standard sizes of lumber without waste. Each of these sections is provided with two transverse cleats 11 and 12, disposed on the under side 70 thereof. The hinges 10 are mounted upon these cleats, which are morticed so that the hinges may be disposed below the surface of the cleats to permit of the two sections 75 being folded together to assume a compact 75 form.

A standard 13, is provided for the purpose of supporting this table top, and comprises four legs 14, 15, 16, 17, which are of any suitable material but preferably cut 80 from lengths of standard size lumber with a miter cut, which results in the ends of the legs being disposed at an angle to the perpendicular, the angle being preferably 45 degrees so that when the legs are disposed at that angle the surface 18, at each end extends in a horizontal plane and is thereby adapted to rest fully upon a smooth 85 surface.

Two of the legs 15 and 16, are joined near 90 their upper ends by a transverse tie-rod 19, which is of such length that the distance between the inner sides of the two legs is only slightly greater than the width of one section of the table top; for the purpose which 95 will appear hereinafter. The other two legs 14 and 17, are also joined by a similar tie-rod 20, which is somewhat longer than the tie-rod 19 to permit of the legs 15 and 16, jointly, being disposed within the legs 14, 100 and 17. The tie-rods 19 and 20 are slightly longer than the width of the sections 8 and 9 when the sections are folded together, so that the folded sections may fit between the pairs of legs with the tie-rods between the 105 ends of the folded sections. The inner set of legs 15 and 16, is pivoted to the other set 14 and 17, by means of bolts 21, dis-

posed about midway of their length, permitting the standard to be folded into the compact form shown in Figure 3.

The transverse cleats have one of their edges beveled inwardly at the same angle as the miter on the legs so that a recess 24, is provided to receive the mitered end of the legs.

It is obvious that any weight coming upon 10 the table or the legs will tend to expand the standard with the result that the ends become more securely engaged with the inwardly beveled cleats. The table top normally tends to hold the standard from 15 collapsing as well as assuring locked engagement therewith and provides an extremely rigid construction.

As a means for further securing the top to the standard a spring strip 25, is pivoted at 20 its center to one of the sections of the top and is adapted to be swung into position to engage the transverse tie-rods. The ends of the spring strip 25 are sprung under the tie-rods to force the tie-rods against the unfolded panels and prevent the possibility of the panels folding while in use. This strip may be of any suitable material adapting it to be bent somewhat but to return to its 25 normal shape when released and is preferably cut from suitable lumber.

In the operation of folding the table this strip is turned until it disengages from the tie-rods and springs back to its normal position flat against the section to which it is 30 fastened and is then turned so as to extend substantially parallel to the edge of that section so as not to interfere with the folding of the top. The standard is then closed partially so that the legs disengage from the recesses whereupon the top is lifted from the standard and folded into the form shown 35 in Figure 5. The standard is then allowed to collapse each tie-rod being then disposed at either end of the folded standard.

40 It will be observed that when the top is folded the sections are spaced apart by the two cleats, the distance between the inner faces of the sections thus being equal to the thickness of two cleats. As a result a space 45 50 55 60 65 70 75 80 85 90 95 100 105 110 115 120 125 130 27, is provided at either end of the folded top which is then placed at a slight angle to the folded standard as indicated by the broken line in Figure 4, and one of the tie-rods is then introduced into the slot and the top is advanced over the tie-rod until the other end is clear of the other tie-rod, whereupon the top is lowered until it is parallel with the folded standard. It is then retracted until the other of the tie-rods is introduced into the other of the spaces. The folded top is thus interlocked with the standard to form a compact portable unit as clearly shown in Figure 3. To hold the top in position about the standard a wire 28, 29, is provided which extends through one of

the legs and is then bent at right angles to form a clip, which also serves to retain the standard in folded form. To facilitate transporting of the folded unit the same leg is provided with a light wire handle 29, 70 which is pivotally mounted thereon.

Whereas I have shown and described a specific embodiment of my invention I do not limit myself to the exact details of construction shown but may employ such other 75 changes and modifications as come within the scope of the appended claims without departing from the spirit of the invention. For instance I have shown and described a table but by changing the proportions the 80 invention may be applied to a folding seat.

I claim:

1. A foldable table comprising a pair of panels, a pair of spaced alined cleats secured to the undersides of the ends of said 85 cleats and having inwardly beveled inner edges, hinges connecting the inner ends and lower sides of corresponding cleats to hinge the panels together; a foldable standard comprising two pairs of crossed leg members pivotally connected at their intersections, the upper ends of said members being pointed and adapted to extend into the channels formed by the bevelled edges of the 90 cleats; tie-rods connecting the upper portions of the leg members of one pair with the upper portions of the leg members of the other pair so as to lie close to the under sides of the unfolded panels; said tie-rods being slightly longer than the width of the 95 panels when folded; and a spring strip pivoted at its center to one of the panels and adapted to have its ends sprung under the tie-rods to force the tie-rods against the unfolded panels, to prevent the possibility of the panels folding while in use. 100 105

2. A foldable table comprising a pair of panels, a pair of spaced alined cleats secured to the undersides of the ends of said panels and having inwardly beveled inner edges, hinges connecting the inner ends and lower sides of corresponding cleats to hinge the panels together, a foldable standard comprising two pairs of crossed leg members pivotally connected at their intersections, the upper ends of said members being pointed and adapted to extend into the channels formed by the bevelled edges of the cleats; tie-rods connecting the upper portions of the leg members of one pair with the upper portions of the leg members of the other pair so as to lie close to the under sides of the unfolded panels; said tie-rods being slightly longer than the width of the panels when folded; and a spring strip pivoted at 110 its center to one of the panels and adapted to have its ends sprung at its center to one of the panels and adapted to have its ends sprung under the tie-rods to force the tie-rods against the unfolded panels, to prevent 115 120 125 130

the possibility of the panels folding while in use; said panels when folded being adapted to fit between the two sets of leg members, with the tie-rods between the ends of the 5 panels.

3. A foldable table comprising a pair of panels, a pair of spaced alined cleats secured to the undersides of the ends of said cleats and having inwardly bevelled inner edges, 10 hinges connecting the inner ends and lower sides of corresponding cleats to hinge the panels together; a foldable standard comprising two pairs of crossed leg members said members being pointed and adapted to

extend into the channels formed by the 15 bevelled edges of the cleats; tie rods connecting the upper portions of the leg members of one pair with the upper portions of the leg members of the other pair so as to lie close to the under sides of the unfolded 20 panels; and a spring strip pivoted at its center to one of the panels and adapted to have its ends sprung under the tie-rods to force the tie-rods against the unfolded panels, to prevent the possibility of the panels folding 25 while in use.

A. G. SMITH.
